C. A. BUTLER,
PIPE TONGS.
APPLICATION FILED APR. 6, 1921.

UNITED STATES PATENT OFFICE.

CHARLES AUGUSTUS BUTLER, OF OKMULGEE, OKLAHOMA.

PIPE TONGS.

Application filed April 6, 1921. Serial No. 458,909.

To all whom it may concern:

Be it known that I, CHARLES A. BUTLER, a citizen of the United States, residing at Okmulgee, in the county of Okmulgee, State 5 of Oklahoma, have invented certain new and useful Improvements in Pipe Tongs, of which the following is a description, reference being had to the accompanying drawing and to the figures of reference marked 10 thereon.

This invention relates to pipe tongs, and more particularly to an improved device for preventing the dulling of the gripping surface of the tongs, due to their constant use.

15 In present devices, of this character, it is customary to provide the jaws of pipe tongs with dies having sharpened edges, a die being held in place on the jaws in any desired manner, such as by means of a wedge-shaped key which fits in a tapered seat and is driven in back of the die so that it holds the die rigidly in one position. In this position, the sharp corner of the die is brought into contact with the outside of the pipe and 25 when the handles of the tongs are squeezed together, this sharp corner is forced into the exterior surface of the pipe to give the tongs a rigid hold on the pipe during the working stroke of the tongs. After this stroke, it is 30 necessary to release the grip on the tongs to bring them back for a fresh grip, and when the tongs are brought back, the die being keyed fast in the jaw of the tongs with its sharp corner in contact with the 35 pipe, necessarily drags the sharp edge of the die over the pipe surface, which in due time wears off the sharp edge of the corner of the die. As soon as the corner becomes dull, the tongs slip and cannot hold the pipe during 40 the working stroke. It is then necessary to take out the die and turn it so that the next sharp corner will act as a gripping surface, and as soon as the four corners have been dulled, the die becomes useless and has to be 45 replaced by a new one.

One of the objects of the present invention is to provide a device for preventing the wearing away or dulling of the gripping surface of the die so that it is not necessary 50 to constantly replace these expensive dies.

Another object of this invention is to provide a construction in which the idle stroke of the pipe tongs circumferentially about the pipe is utilized to maintain the gripping 55 surface of the die in sharpened condition.

Another object of the invention is to provide an improved construction for mounting the dies in the jaws, which permits their ready removal and adjustment.

Another object of this invention is to provide a mounting for these dies which acts as a wear plate for contact between the tongs and the pipe section.

These and other objects will in part be obvious and will in part be hereinafter more 65 fully disclosed.

Referring more particularly to the accompanying drawings:—

Figure 1 is a perspective view of the pipe tongs in gripping position on the pipe; 70

Fig. 2 is a sectional view thereof;

Fig. 3 is a sectional view on the line 3—3 of Fig. 2, and

Fig. 4 is a detail view partly in section of the keepers or die retaining members. 75

In general, the tongs comprise the usual pivoted jaws, which in the present instance are recessed to receive the dies; in addition, each jaw is provided with a die clip or keeper for retaining the dies in the jaws. 80 Each keeper has an arcuate shaped face spaced slightly from and conforming to the inner circumference of the pipe about which the tongs fit. The inner face of this keeper is provided with a suitable number of apertures through which project the biting portions of the dies. The dies which are substantially square-shaped and provided with four sharpened corners, fit in substantially square-shaped seats in the keepers. The two lateral walls of these seats are flared slightly away from a line at right angles with the back wall of the recess so that the square dies are permitted to shift laterally in their seats. In order that the inner corners of the dies will contact with the corresponding corners of the seats, the seat corners are cut away. By means of this construction, on the working stroke of the pipe tongs, the sharp corner of the die will 90 be forced into the periphery of the pipe and will form a firm grip so that the pipe can be turned, but due to the flared lateral walls of the recess, on the idle stroke, the square dies can rock in their seats so that the sharp 95 gripping corner will swing clear of the pipe to permit the tongs to move circumferentially of the pipe. The flat side of the die adjacent the sharpened corner will then 100 scrape circumferentially of the pipe, and in 110

this way keep the corner sharp and in good gripping condition.

Referring more particularly to the accompanying drawing, the tongs comprise the 5 two jaws 1 and 2 pivoted at 3 and are shown as encircling the pipe section. Each one of these jaws is suitably recessed to receive its die or dies 4 and is provided with a die clip for holding the dies in position on the jaw.

10 While these die recesses substantially correspond to the size and shape of the dies, they are slightly altered to permit an automatic shifting of the die, as will be presently described.

15 While many constructions are practicable, I prefer to hold the dies in their seats or recesses by means of arcuate clips or keepers mounted on the inner face of the jaw sections. For instance, the larger jaw 3 is provided with a relatively long arcuate clip 6 formed with an intermediate wearing face or wall 7 which lies parallel to the working face of the jaw, and two integral upper and lower flanges 8 and 9, respectively. These 25 flanges pass over the upper and lower side faces 10 and 11, respectively, of the jaw. This clip 6 is apertured as at 12 to receive a pivot pin 13 passing through registering apertures in the jaw. The opposite end of 30 the clip is formed with hemi-spherical recesses 14 for receiving a locking pin to hold the clip in closed position. At suitable spaced intervals corresponding to the number of dies mounted in said clip, the inner 35 wall 7 of the clip 6 is provided with an aperture or apertures 15 through which the sharpened end of the die projects. This inner wall 7 of the clip not only constitutes a wearing surface for the tongs, inasmuch 40 as it is the portion of the jaw which comes into contact with the peripheral face of the pipe, but it also constitutes a means for retaining the dies in their seats in the jaw and permits them to automatically shift laterally 45 as will now be described.

As a means for permitting this shifting of the dies, I prefer to provide the inner face of the jaw with recesses or die seats corresponding in size and shape to the dies, such 50 recesses having back walls 16 and side walls 17, the side walls being arranged at an obtuse angle relative to the back walls. These recesses are adapted to receive the square shaped dies provided with the sharpened 55 corners.

From this construction, it will be observed that when the tongs are gripped together, the sharp corners of the dies projecting through the apertures 15 in the clips contact 60 with the periphery of the pipe and are forced to bite into the pipe as the tongs are moved in one direction circumferentially of the pipe. Thus the tongs will carry the pipe sections around with it during the working 65 stroke. When the tongs are released, to

bring them back for another turn, the dies will shift in their seats by means of the flared arrangement of the lateral walls 12 so that the biting corner 18 of each die 4 will swing clear of the periphery of the pipe. 70 At the same time, the face 19 of the die adjacent the corner 18 will drag along the periphery of the pipe and will thus maintain this corner 18 sharp.

During this rocking action, it is imperative 75 that the inner sharpened corners of the die do not come into contact with the walls or corners of the recess. In order to take care of this, the corners of the recess are cut away as at 20. This also provides a means 80 whereby the dies will automatically clear themselves of scale and dirt, the scale and dirt falling through to the bottom of the dies and then through suitable apertures in the clips. Inasmuch as the construction of the 85 other jaw 2, its clip and die and mode of operation is identical, no further reference will be made to it.

Any desired means for retaining the clips 90 in place may be used. In the present instance, each die is provided with a recess 21 for seating retaining pins 22 and 23 which are pressed outwardly by means of spring 24 through opposite faces of the jaw. These pins 22 and 23 are adapted to engage in the 95 semi-spherical recesses 14 of the clip from which they may be released by an inward pressure. To remove the dies, the pins 22 and 23 are pushed, which releases the clip 6 so that it can swing outwardly on pin 13, 100 after which the dies 4 can be taken out and replaced. The clips can then be swung back and the pins 22 and 23 snap into place.

It is obvious that minor changes in the 105 details of construction and in the arrangement of parts may be made without departing from the spirit of the invention as set forth in the appended claims.

Having thus described the invention, what I claim as new and desire to secure by Let- 110 ters-Patent, is:—

1. A pipe tongs comprising pivoted jaws adapted to receive a pipe therebetween, each of said jaws being provided with a suitable number of die recesses having lateral walls 115 arranged at an obtuse angle to the rear wall, a substantially square-shaped die in each recess, said dies having comparatively sharp corners for gripping the pipe, whereby on movement of said tongs in one direction circumferentially of said pipe said dies will shift in their recesses to cause said dies to bite into the pipe and on reverse movement of said tongs said biting corners will shift clear of said pipe. 120

2. A pipe tongs comprising pivoted jaws adapted to receive a pipe therebetween, each of said jaws being provided with a suitable number of die recesses having lateral walls arranged at an obtuse angle to the rear 130

wall, a substantially square-shaped die having relatively sharp pipe gripping corners arranged in each die recess, to permit said dies to shift in their recesses, the corners 5 of said recesses between the rear and lateral walls being cut away to permit the adjacent corners of said dies from contacting with the walls of said recess.

3. A pipe tongs comprising pivoted jaws 10 adapted to receive a pipe therebetween, one of said jaws being provided with a recess, a die mounted in said recess, a keeper carried by and lining the inner wall of said jaw, said keeper being apertured to permit the 15 gripping face of the die to project therethrough to engage the pipe, said die and recess being constructed and arranged so that the gripping portion of the die automatically grips said pipe on movement of 20 said tongs in one direction circumferentially of the pipe and automatically moves said

gripping portion clear of said pipe on the reverse motion of said tongs.

4. A pipe tongs comprising pivoted jaws adapted to receive a pipe therebetween, one 25 of said jaws being provided with a plurality of recesses, a die mounted in each recess, a keeper lining the inner wall of said jaw and apertured to permit the gripping faces of the dies to project therethrough to engage the pipe, said keeper being movably mounted on said jaw so as to permit the ready adjustment of said dies, said dies and recesses being constructed and arranged so that the gripping portion of the die automatically 30 grips said pipe on movement of said tongs in one direction circumferentially of the pipe and automatically moves said gripping portion clear of said pipe on the reverse motion of said tongs. 40

In testimony whereof, I affix my signature.
CHARLES AUGUSTUS BUTLER.
